UNITED STATES PATENT OFFICE.

ALEXANDER R. McDONNELL, OF LITTLETON, MAINE.

HORSE-BRUSH.

SPECIFICATION forming part of Letters Patent No. 654,751, dated July 31, 1900.

Application filed May 1, 1900. Serial No. 15,117. (No model.)

To all whom it may concern:

Be it known that I, ALEXANDER R. McDONNELL, a citizen of the United States of America, and a resident of Littleton, in the county of 5 Aroostook and State of Maine, have invented certain new and useful Improvements in Horse-Brushes, of which the following is a specification.

My present invention relates to a horse-brush adapted for use especially after the hair has been combed with a bristle brush. The brush herein described serves very effectually to give a gloss and to remove the dandruff and dirt that have been loosened by the combing. 10 My invention consists in providing a base-plate or backing, of leather, of any convenient shape, but preferably like a thin sheet, but thick enough to give strength and stiffness. Upon one side of this base-plate, of leather 15 or similar substance, is placed a series of ridges running parallel to one another and having notches on the edges, while the lower surfaces of the parts forming the ridges are fastened to the base-plate. Running at an angle to the ridges is a second series of ridges 20 practically like the first and also parallel to one another and having notches on their narrow edges, while the under surfaces are fastened to the base-plate, and it is to be understood that the ridges are made from rubber 25 in a single piece, so that by fastening the combination of crossing ridges to the plate there is provided the complete brush ready for sale and use. The cross-section of the ridges is approximately triangular.

Figure 1 is a plan of the brush, showing in one view the base-plate and the notched ridges which in actual practice would cover the complete surface of the plate or as much thereof 30 as might be desired. Figs. 2 and 3 are cross-sectional views of the ridges at the notches, so that one-half of a notch is shown in each view.

A is the base-plate, of leather, formed in a

sheet, one side of which appears, the other 45 side being plain and having nothing to do with the invention; but there may be a handle on the other side.

B shows the tops or edges of triangular ridges which are seen in section in one or two of the 50 figures as lettered. The edges B need not be sharp like a knife-edge, but are preferably very narrow, as they act as the scraping or polishing edges upon the hair when the brush is in use. They are parallel to each other 55 preferably. Between these ridges are other ridges whose edges are lettered C. They are the narrow tops of the triangular ridges meeting the first series at an angle, so as to form four-sided figures or diamond-shaped figures, 60 as indicated. The edges B are on the series of ridges D, and the edges C are on the series of ridges E. Cut into both series of ridges are notches G, so that the edges in use will the more effectively polish and clean the hair. 65

The operation of the brush need not be set forth, for it is simply rubbed upon the hair of the animal, and thereby serves a useful purpose.

I claim as my invention—

1. A horse-brush consisting of the combination of a leather base-plate, and a piece of rubber fastened thereto, and having different series of narrow-edged ridges provided with notches and crossing one another.

2. A horse-brush, consisting of the combination of a base-plate, rows of ridges of triangular cross-section, and having narrow edges at their tops, and a second series of triangular ridges having narrow edges, crossing 80 the first row or series at an angle, and formed of a soft yielding material.

In testimony whereof I have hereunto subscribed my name this 20th day of April, 1900.

ALEX. R. McDONNELL. [L.S.]
